UNITED STATES PATENT OFFICE.

WILLIAM JOSEPH KELLY, OF MANCHESTER, ENGLAND, ASSIGNOR OF ONE-HALF TO EDWARD TURNER WHITELOW, OF SAME PLACE.

STOPPERING BOTTLES.

SPECIFICATION forming part of Letters Patent No. 514,178, dated August 6, 1895.

Application filed March 18, 1895. Serial No. 542,252. (No model.)

To all whom it may concern:

Be it known that I, WILLIAM JOSEPH KELLY, a subject of the Queen of Great Britain and Ireland, and a resident of 42 Stanley Street, 5 Cheetham, Manchester, county of Lancaster, England, have invented certain Improvements in Stoppering Bottles, of which the following is a specification.

This invention relates to bottles and flasks 10 provided with a removable back-pressure valve and seat capable of insertion into a bottle-neck after filling the said bottle, and also capable of being removed without breaking or injuring the bottle or any part of the 15 device.

The object of the said invention is to make such stoppers more durable and satisfactory, and the said invention consists in the construction and combination of parts herein- 20 after set forth and claimed.

In the accompanying drawings, Figure 1 represents a vertical central section of a bottle-neck and the upper part of a bottle provided with one form of valve and valve-seat adapted 25 to such use. Figs. 2, 3, 4, and 5 represent similar views of other forms of the same, Fig. 2 omitting the bottle below the neck. Fig. 5^a represents a vertical sectional view of a bottle-neck provided with a protecting cap or cover 30 for the valve secured to the valve-seat, this being the preferred form of my invention, and Figs. 6, 6^a, 7, and 7^a represent detail views of modified forms of the valve and its seat.

In all of the said figures *a* designates the 35 neck of the bottle or flask, *b* the valve having a stem *b'*, and *c* a supporting-ring of rubber or other elastic material, which in Figs. 1, 2, and 3 constitutes also the valve-seat.

In Fig. 1 the periphery of the valve proper 40 is provided with radially-extending guide-*stud*s *b*³, which, by coming in contact with the inner face of the neck of the bottle, compel the said valve to rise and descend vertically without tilting. A cross-bar *b*² on the lower 45 end of the valve-stem comes in contact with the under side of the valve-seat *c*, which is in this figure a solid ring of rubber or other elastic material, adhering to the smooth inner face of the bottle-neck, but easily introduced 50 into and withdrawn from the same. In Fig.

2 the said seat is much longer and thinner, retaining the annular form, but supporting the valve on an inwardly-extending annular bottom-flange *c*⁴, having a central opening *c*⁵, instead of supporting it on the top of the said 55 ring or annular seat, as in Fig. 1.

Fig. 3 is in all respects like Fig. 1, except that the annular seat *c* is provided with an external bead *c'* surrounding its middle part and integral therewith, and fitting into a 60 similarly-shaped recess formed by an outward bulge *a'* of the bottle-neck.

In Fig. 4 the neck is provided with this recess, which is made broader and more shallow, but the rubber ring *c* is made small enough 65 to fit therein with about one-half of the ring extending into a corresponding recess of an inelastic valve-seat *e*, which supports the said valve. At *e'*, above and below the said ring, the said seat is of approximately the interior 70 diameter of the bottle-neck. The ring *c* serves merely as a means of support and removable attachment.

In Fig. 5 the rubber ring *c* is substantially that shown in Fig. 1, except that it has a convex exterior which fits into a shallow concavity provided for it in the inner face of the bottle-neck. In this instance the seat *e* is thinner than in Fig. 4 and provided at the top with an outwardly-extending annular flange *e*², which rests on the top of the said rubber ring, the body of the said seat fitting within the latter. In Fig. 5^a this flange *e*² is omitted, and the upper end of the said seat *e*, extending above the said ring, is externally screw-threaded to engage similar threads on the inner face of the lower end of a cap-shaped stop-frame *d*, which is screwed down against the said ring and has a central opening *d'* for the outward passage of the liquid. This frame prevents the valve from being dislodged if the cross-piece *b*³ should be detached or should fail to answer its purpose. Sometimes, as in Figs. 7 and 7^a, I use two of these cross-pieces *b'*, instead of one, with each valve-stem, and sometimes I extend the stem down through a solid part of the valve-seat and provide its lower end with a nut to prevent detachment. The valve-seat *c* in this case has only its upper part made of rubber, the lower 100

part c^5 being of inelastic material and provided with openings g for the passage of the liquid through its sides.

The operation of the valve while the bottle 5 or flask is in use is substantially as in devices of the same general character already used and known. The same is true of its insertion and removal.

Having thus described my invention, what 10 I claim as new, and desire to secure by Letters Patent, is—

A flat disk valve b provided with a stem b' and cross-piece b^2 , in combination with a tubular valve seat e having its upper end screw-

threaded, a stop-cap d which is screw-threaded 15 to turn on the said upper end, and a rubber ring c surrounding the said seat to hold it in the neck of a bottle the upper end of the said valve seat being extended above the said ring, substantially as set forth.

In testimony whereof I have signed my name to this specification in the presence of 20 two subscribing witnesses.

WILLIAM JOSEPH KELLY.
